COMBINED LONG AND SHORT WAVE
RECEIVERHans Otto Roosenstein, Berlin, Germany, as-
signor to Telefunken Gesellschaft fur Draht-
lese Telegraphie m. b. H., Berlin, GermanyApplication October 1, 1931, Serial No. 566,197
In Germany February 19, 1931

6 Claims. (Cl. 250—20)

The present invention relates to an arrangement adapted to receive waves of different orders of magnitude.

In Patent No. 1,897,735, issued February 14, 5 1933, a receiver arrangement has been disclosed adapted to waves of different orders of magnitude, the same being characterized by the feature that a tube provided in the long wave receiver arrangement is designed to be changed 10 over for short wave reception in a super-regenerative circuit scheme. The present invention is concerned with a special form of construction of such an arrangement in this manner that the interruption frequency furnished from the interruption frequency tube is transferred, or fed, to 15 the short wave receiver tube by the same device which insures the regeneration of the last mentioned tube in the long wave circuit arrangement.

The novel features which I believe to be characteristic of my invention are set forth in particularity in the appended claims, the invention itself, however, as to both its organization and method of operation will best be understood by reference to the following description taken in 20 connection with the drawing in which I have indicated diagrammatically one arrangement for carrying my invention into effect.

One embodiment of this idea is illustrated in Fig. 1, wherein 1 denotes the antenna which 25 serves for long wave reception, while 2 the aerial used for short wave reception. The screen grid tube 3 in the case of long waves acts as a radio frequency amplifier, while by cutting in circuit the condenser 5, by means of the switch 21, upon 30 reception of short waves, it is caused to generate the interruption frequency.

In order to receive short waves it is also necessary to place the switch 22 upon the contact 23 with the result that the short wave oscillatory 35 circuit 20, 7, 10 is completed. By the interruption frequency oscillation present in the circuit 15, 16, alternating current potentials of this frequency are induced in the coil 14, and these potentials are fed to the tube 4 by way of the variable con- 40 denser 13 and the radio frequency choke coil 8. The latter just like choke coil 18 may be regarded as a short-circuit only for the long waves and for the interruption frequency.

The choke coils 9 and 25, on the contrary, act 45 as practically infinitely high reactances for the interruption frequency and the longer incoming waves. If long waves are to be received with the arrangement then the switch 21 is opened, and switch 22 is placed on contact 24. The tube 3 50 then operates only as a radio frequency amplifier,

and the radio frequency potentials acting across the condenser 16 are readily fed to the grid of tube 4 through the circuit including conductor 30, condenser 31 and switch 22. In this instance, the series arrangement of condenser 13 and coil 14 acts regeneratively as far as tube 4 is concerned.

As a general rule it is necessary that the grid leak 25 for long wave reception should be other than the grid leak resistance 19 for short wave 60 reception. It has frequently proved advantageous to associate this resistance at a point presenting a certain potential difference relative to the negative end of the filament. Resistance 19 under certain circumstances may be made very 65 low, or even equal to zero. To the terminals 12 of the apparatus may be connected a conventional audio amplifier, say, a resistance coupled amplifier. The resistance 11 in the plate lead of tube 4 in this latter instance is the coupling resistance 70 of the first tube of the resistance coupled amplifier.

The operation of the present arrangement will be understood more clearly if the system be considered as comprising a super-regenerative receiver for short waves, the audio frequency output voltage for a following audio frequency amplifier tube (not shown) being taken off across the resistor 11 for both the super-regenerative circuit, and for the long wave receiving system 80 which includes a tuned radio frequency amplifier followed by a regenerative detector, the output of the regenerative detector being impressed across the resistor 11.

Considering, first, the operation of the system 90 from the viewpoint of the reception of long waves, it is necessary to open switch 21, and connect switch 22 to contact 24 to receive long waves. With these connections made the antenna 1 collects the long wave signal energy, and the collected energy is impressed upon the tunable input circuit 32 connected between the control grid and cathode of the screen grid tube 3. The anode potential for tube 3 is provided by a battery 33 and lead 34 through the long wave radio frequency choke 26. The tube 4 functions as a regenerative detector, the tuned circuit 15, 16 being connected between the control grid and cathode of tube 4.

The anode circuit of tube 4 includes the audio 105 frequency coupling resistor 11 and the long wave radio frequency choke 9. As stated heretofore the detected output of tube 4 is taken off across the resistor 11 and utilized in any desired manner. The path including the variable condenser 110

13 and coil 14, inductively coupled to coil 15, provides a regenerative feed-back path between the anode of tube 4 and its cathode circuit. Detection is performed by the condenser 31 and grid 5 leak 25 connected across the input electrodes of tube 4.

To receive short waves, the switch 21 is closed, and the switch 22 is moved into contact with the terminal 23. With these connections made, the 10 short wave signal energy is picked up by the antenna circuit 35 containing coil 2 which is inductively coupled with the coil 7 disposed in an oscillator circuit of the Hartley type. This oscillator circuit comprises the tube 4 having connected between its anode and its control grid the path including coil 7, the condenser 10, and the second coil 7', this said path being shunted by the variable tuning condenser 20. The point 15 23 of this tunable circuit is connected through the path including the coil 13 and resistor 19, to the cathode lead of the tube 4. Potential for the anode of the tube 4 is provided through a path which includes battery 33, lead 34, the audio frequency coupling resistor 11, the interruption frequency choke coil 9 and the short wave 20 25 radio frequency choke coil 8.

The tube 3 and its associated circuits now function as a source of interruption frequency energy for the oscillator circuit. Thus, the tunable circuit 15, 16 and the tunable circuit 32 connected between the grid and cathode of tube 3 are resonated to the same desired interruption frequency. Potential for the anode of tube 3 is fed through the choke coil 26, and the interruption 30 35 frequency itself is fed to the oscillator circuit through the path which includes the coil 14, magnetically coupled to coil 15, and the variable condenser 13 which may be adjusted to control the amount of super-regeneration.

40 It is not believed necessary to describe in detail the theory underlying the super-regenerative action since those skilled in the art are well acquainted with such theories. It is sufficient to point out that regeneration beyond the normal 45 point of oscillation into the range of super-regeneration is carried out in the oscillator circuit including tube 4 by utilizing interruption frequency to vary the plate potential of tube 4 at the interruption frequency rate. This results in a 50 periodic damping of sustained oscillations, the periodicity depending on the interruption frequency.

While I have indicated and described one arrangement for carrying my invention into effect, 55 it will be apparent to one skilled in the art that my invention is by no means limited to the particular organization shown and described, but that many modifications may be made without departing from the scope of my invention as set 60 forth in the appended claims.

What I claim is:

1. In combination, in a combined long and short wave receiver, an electron tube provided with a tunable input circuit and a tunable output circuit, 65 a second electron tube provided with a pair of input electrodes connected across the tunable output circuit of said first tube, means in the anode circuit of the second tube adapted to couple it to a load circuit, a regenerative feed-back path connected between the anode circuit of the second tube and the tunable output circuit of the first tube, a long wave antenna coupled to the tunable 70 input circuit of the first tube, a short wave antenna, means for coupling the input and output

circuits of the first tube to render the said first tube and its associated circuits capable of producing interruption frequency energy, and means for disconnecting the input electrodes of the second tube from the tunable output circuit of the first tube and instead coupling the anode and grid of the second tube to the short wave antenna. 80

2. In combination, means for collecting low frequency signal energy, means for collecting high frequency signal energy, a regenerative amplifier tube having an input circuit coupled to said second named means, means for tuning said input circuit to the high frequency energy, a second amplifier tube having an input circuit coupled to said first named means including means for tuning said circuit to the low frequency energy, said second amplifier tube also having an output circuit, a feedback connection between the input and output circuits of said second amplifier to cause it to generate oscillations at an interrupting frequency, and additional means coupling the output circuit of said second amplifier to said regenerative amplifier for feeding energy at an interrupting frequency to said regenerative amplifier when receiving said high frequency signal energy. 85 90 95

3. In combination means for collecting low frequency signal energy, an amplifier tube having an input circuit coupled to said means and including means for tuning it to the low frequency signals, an output circuit connected to said tube, a feedback connection between said input and output circuits to cause said amplifier to generate oscillations at an interrupting frequency, means for collecting high frequency signal energy, a regenerative detector having an input circuit coupled to said last named means and including means for tuning said input circuit to the high frequency signals, and additional means, including a resonant path coupling the output circuits of the said amplifier tube and regenerative detector for feeding energy at an interrupting frequency to said detector when receiving high frequency signal energy. 105 110

4. The combination of the preceding claim in which the feedback connection of said amplifier tube includes a switch and condenser connected in series. 115

5. The combination defined in claim 2 in which the output circuit of said regenerative amplifier tube includes a high resistance and choke coil 120 125 connected in series, said resistance providing a coupling means adapted to couple said amplifier to a succeeding amplifier.

6. In a radio receiver, the combination of a source of low frequency signal energy, an amplifier tube having an input circuit coupled to said source and including means for tuning it to the low frequency energy, an output circuit connected to said tube, a feedback connection between said input and output circuits to cause said tube to 130 135 generate oscillations at an interrupting frequency, a source of high frequency signal energy, a regenerative detector having an input circuit coupled to said last named source and including means for tuning said input circuit to the high frequency 140 energy and means coupling the output circuit of said amplifier tube to said regenerative detector including the series connection of an inductance coil and a variable condenser for feeding energy at an interrupting frequency to said detector when receiving high frequency signal energy, adjustment of said condenser serving to control the amount of regeneration in said detector. 145
